UNITED STATES PATENT OFFICE.

JOHN GRIER, OF RIXFORD, PENNSYLVANIA.

ADJUSTABLE STANDARD FOR WAGON-BOLSTERS.

SPECIFICATION forming part of Letters Patent No. 237,519, dated February 8, 1881.

Application filed December 20, 1880. (Model.)

To all whom it may concern:

Be it known that I, JOHN GRIER, of Rixford, in the county of McKean and State of Pennsylvania, have invented certain new and useful 5 Improvements in Bolsters and Standards for Wagons or Sleighs; and I do hereby declare the following to be a full, clear, and exact description of the invention, such as will enable others skilled in the art to which it pertains 10 to make and use it, reference being had to the accompanying drawing, which forms part of this specification.

My invention relates to an improvement in combined wagon bolsters and standards; and 15 it consists in a bolster having horizontal guides formed on each of its sides, with a standard which is made adjustable back and forth upon the bolster, and which has extensions formed on each edge, so as to catch under 20 and over the guides on the bolster, whereby the standard can only be removed from the bolster by sliding it off at one end, as will be more fully described hereinafter.

The object of my invention is to fasten the 25 standard in place upon the bolster by means of a pin or bolt, which is passed down through the top of the standard into the bolster, and which is made instantly removable, so that the standard can be adjusted back and forth 30 upon the bolster without the necessity of having to remove the usual nuts and bolts which have heretofore been used for fastening devices.

The accompanying drawing represents a 35 perspective of my invention.

A represents an ordinary wagon-bolster, which has a horizontal guide or flange, C, formed upon or secured to each of its sides. Upon the top edge of this bolster is secured a 40 metallic plate, D, through which suitable holes are made at equal distances apart, and which plate serves to prevent all wear and tear upon the bolster as the standard is moved back and

forth. This standard G has a suitable extension, I, projecting down from each of its edges, 45 and which flanges have horizontal recesses formed in their inner sides for the purpose of fitting over and under the guides on the bolster, as shown. As these flanges form a part of the standard and catch under these guides 50 it is evident that the standard cannot be lifted upward off of the bolster, but that the standard must be slid along to the end of the bolster before it can be removed. Through the standard, just over the bolster, is made a hole, 55 J, through which a pin or bolt of any kind is passed down into the bolster, so as to hold the standard in place. This pin or bolt is instantly removable, and it is only necessary to pull the pin out and then move the standard 60 along to adjust it into any desired position.

Heretofore standards have been made adjustable back and forth upon the bolster; but they have been held in place by means of bolts which are passed horizontally through both 65 standard and bolster, and which are troublesome to adjust; and this I disclaim.

The object of my invention has been to make the standard readily adjustable back and forth without the use of tools of any kind. 70

Having thus described my invention, I claim—

The combination of the bolster having the horizontal guides or flanges formed upon its sides, with the standard having flanges projecting down over its edges, so as to catch over 75 and under the guides, and a means for fastening the standard in place, substantially as shown and described.

In testimony that I claim the foregoing I have hereunto set my hand this 16th day of December, 1880.

JOHN GRIER.
